2,060,670

SUBMARINE TELEVISION

Hans Hartman, Monaco, Monaco

Application November 13, 1931, Serial No. 574,835

5 Claims. (Cl. 61—69)

The present invention relates to a submarine television apparatus and the main object in view is, to provide means for visualizing the images of submerged objects or other submarine images 5 distantly thru electric television upon a screen or other medium or utilizing said electrically transmitted images for direct photographic reproduction.

Other objects are to provide in combination 10 with submarine television means submarine photographic cameras for still and moving pictures and other devices for submarine research, exploration and salvage work.

The main feature of my present invention is 15 not any particular construction or technical arrangement but the utilization of existing or still unknown systems of electric television for submarine purposes in combination with watertight and water pressure resisting compartments or 20 chambers, shells and the like and also, the combination of electric television means with photographic cameras and other useful devices which can be utilized for submarine purposes.

As it is evident that, at the present development 25 of the art, this main feature of my invention may be attained in varying technical combinations and by using various technical constructions, it is obvious that I cannot limit myself to any particular embodiment of the invention, 30 one of which I am describing herein and showing in the accompanying drawing merely to illustrate one possible combination of parts, whereby equal numerals designate equal or similar parts.

In a steel globe 1, closed watertight by a removable steel cover 2, at one side in a vertical 35 direction, and held in place by screws 2a, having a plurality of circularly arranged larger openings, closed by heavy glass or quartz-lenses 3, attached watertight to the cover by metal rings 40 3a, are inserted an equal number of electric lamps 4, the light of which is intensified and reflected thru said lenses 3, by means of reflectors 5, to the exterior so as to illuminate the water in front 45 of said cover, when globe 1, is submerged.

In the center of the cover 2, are provided two smaller openings, closed also watertight by means of two lenses 6, and 7, held in place by a metal-ring and cushioned at both sides by washers or 50 gaskets as indicated in heavy black lines. Thru lens 6, an image of the illuminated exterior will pass into the globe 1, and guided by means of a double prism 8, it will fall thru the apertures of a scanning disk 9, upon a photo-electric cell 10, 55 the latter sending feeble electric impulses which

may be amplified in any manner known to those skilled in the art, by means of electric conductors and a cable 19, to a television receiving apparatus on board of the vessel from which the globe 1, has been lowered into the water. 5

The second lens 7, will lead the same image from the exterior thru a similar double prism 11, to the lens of a photographic motion picture camera 12, which is driven electrically and may be controlled from the ship. 10

As the entire apparatus may be preferably lighter than the water it displaces, a low voltage motor 13, attached (with its shaft in a vertical position) to the lowermost part of globe 1, will force the same down by rotating its propeller 14, in a predetermined direction. Above the globe 1, is disposed a high pressure cylinder 15, containing compressed air. The same will pass thru a reducing valve 16, actuated by increasing water pressure, during the descent of the globe 20 into greater depths, into its interior, so as to increase the internal pressure resistance of the globe 1, which may be at the start already filled with compressed air to a certain degree. 15

17 designates adjustable connectors and 18, 25 additional tubular lamps or luminous tubes to increase the submarine illumination, while 19, is an electric cable and 20, a safety valve to allow the compressed air to escape when the globe 1, raises to the level and the air pressure within 30 it surpasses the water pressure.

The lamps 4, may be protected against the internal air pressure either by a steel partition arranged behind the cover 2, or the reflectors 4, may encase each lamp individually against said 35 compressed air. The scanning disk 9, is driven in synchronism with a similar disk in the television receiver on board the ship by an electric motor, not shown, in the usual manner. The electric motor 13, driving propeller 14, may be 40 exposed to the sea water, to avoid friction as long as the electric current does not pass over 10 volts, as at so low voltage no short-circuit can be caused and the electrical losses will be 45 small.

The tubular lights 18, may be of a gas-filled type or may contain short tubular incandescent lamps, protected by a heavy quartz or glass envelope, sealed watertight. The current to be used to be preferably of high voltage, direct current, 50 and the lamps connected in series, so as to permit the use of a thin, flexible cable and to reduce losses therein. Separate submarine illuminators 55 may also be utilized, being lowered near the above described apparatus or near the objects to be ex- 55

5 amined or photographed, by means of a second cable and alternating current in combination with transformers may then be used, which would disturb the feeble electric impulses of the photo-electric cell 18, if passing thru the same cable wherein the conductors of said cell 18, are embedded.

10 The modus operandi of the described embodiment of my submarine television apparatus is as follows:

15 Assuming that the apparatus is lowered into the sea from a suitable vessel by means of the electric cable 18, after the cylinder 15, has been filled with air at a high pressure and an electric circuit closed thru the motor 13, and also thru the lamps 4, and 18, and the motor rotating the scanning disk 8, is running in synchronism with a similar motor and scanning disk in the receiving apparatus, installed in a darkened cabin of the ship, 20 an image of the illuminated area under water will be transmitted and appear upon a screen or the like.

25 As soon as anything of sufficient interest becomes visible, an observer may close an electric circuit thru the motor of the motion picture camera or thru an electrical mechanism of any photographic still camera so as to obtain photographic records of what can be seen at that moment in the television receiving apparatus, 30 co-operating with the submarine television sending device described.

35 It shall be pointed out that I do not wish to limit myself to the use of a television system utilizing a perforated scanning disk or to any one particular other system of receiving and transmitting television images. However, at the present development of the art of television, the use of a scanning disk appears to be preferable for submarine television to any other known system, 40 due to its simplicity and compactness, as against the use, for example of revolving mirrors and polarizing prism, etc.

45 To increase the brilliancy of illumination, additional submarine lights may be disposed either directly around and upon the globe 1, and being fed with the necessary electric current by the

same cable, or by additional cables. Or said additional submarine lights may form separate units and be supplied with electric energy by separate cables.

5 From the vessel the submarine television images or electric impulses of the photo-electric cell 18, may be transmitted by wireless, after having been sufficiently amplified, to landstations and broadcasted by the same to a multitude of television receiving apparatus distributed over a wide area. Thus persons far away may see what at 10 that moment the submarine television apparatus described herein produces as images of the illuminated area deep below the water level.

15 Having thus described my invention, what I claim as new is:

1. A submarine television apparatus comprising a hermetically sealed casing, electrically driven television and photographic means in said casing in combination with electric submarine illuminators. 20

2. A submarine television apparatus comprising a watertight sealed casing, means to lower said casing into the water, electrically driven television receiving and transmitting means and a photographic camera within said casing. 25

3. A submarine television receiver comprising a watertight closed chamber, electrically driven and distantly controlled television image receiving means and a motion picture camera within said chamber. 30

4. A submarine television receiver and image transmitter comprising a watertight closed chamber, electrically driven and distantly controlled electric television image receiving and transmitting means and photographing apparatus within said chamber in combination with electric illuminating means adapted to be used under water. 35

5. A submarine television apparatus in combination with submarine photographing means comprising a watertight closed chamber, electrically driven and distantly controlled electric television images receiving and transmitting means and photographing apparatus within said chamber. 40

HANS HARTMAN.
